UNITED STATES PATENT OFFICE

2,582,495

GARMENT HANGER

Walter Ludwig, Detroit, Mich., assignor to L. A. Young Spring & Wire Corporation, Detroit, Mich., a corporation of Michigan

Application November 7, 1946, Serial No. 708,285

4 Claims, (Cl. 223—92)

1

This invention relates to improvements in garment hangers.

The main objects of the invention are:

First, to provide a garment hanger comprising a suspending hook of wire and a supporting yoke of tubular cross section and of fibrous material, in which both the yoke and suspending hook are conformed and shaped to facilitate quick assembly of the parts and in a manner that does not weaken the yoke portion.

Second, to provide an efficient garment supporter of the type above described in which the tubular yoke of fibrous material is conformed and shaped for strength and rigidity and adapted to smoothly engage the garments supported thereon.

Third, to provide a garment hanger having these advantages which is attractive in appearance and economically produced.

Objects relating to details and economies of the invention will appear from the description to follow. The invention is defined in the claims.

A preferred embodiment of the invention is illustrated in the accompanying drawing, in which:

Fig. 1 is a side elevation of the garment hanger embodying the features of the invention.

Fig. 2 is a bottom plan view of the garment hanger showing the longitudinally recessed under wall of the yoke portion.

Fig. 3 is an enlarged view in section of the outer end portion of a yoke arm, taken on the line 3—3 of Fig. 1.

Fig. 4 is an enlarged view in section of a garment supporting arm adjacent the apex of the yoke, taken on the line 4—4 of Fig. 1, and

Fig. 5 is an enlarged fragmentary view centrally of the yoke, partially in section on the line 5—5 of Fig. 1.

Referring to the drawing, the garment hanger comprises a yoke 1 having downwardly diverging garment supporting arms 2. This yoke in the preferred embodiment of the invention is formed of a paper tube. At the apex of the yoke the side walls are collapsed horizontally into abutting relation as shown at 3 in Figs. 1 and 5 to facilitate attachment of a suspending hook to the yoke as hereinafter described. The arms 2 adjacent the collapsed central portion 3 are conformed or shaped to provide the downwardly bent or curved portions 4 as shown in Fig. 1. To facilitate the bending of the tubing and to give rigidity to the tubing in the curved or bent portions 4, the under wall of the tubing is collapsed upwardly centrally and longitudinally of the yoke into sub-

2

stantially abutting relation with the upper wall of the tubing to form the longitudinal groove-like recesses 5 in the bottom wall as shown in Figs. 2 and 4. The yoke arms 2 are further shaped or conformed at the outer ends thereof to provide the relatively smooth downwardly bent or curved shoulder engaging portions 6. To facilitate the downward bending of these end portions and to give rigidity to the same the under wall of the tubing is collapsed longitudinally centrally of the yoke into substantially abutting relation with the upper wall of the tubing, as shown in Figs. 2 and 3, the groove-like recesses 1 in the bottom wall extending longitudinally thereof being formed in such shaping operation.

The tube of the yoke is formed of a plurality of plies or layers of paper as conventionally shown in Figs. 3, 4 and 5 which may be convolutedly or otherwise wound into tube formation. The central collapsed portion 3 and the downwardly bent collapsed portions 4 and 6 of the yoke arms may be collapsed and curved or conformed to shape in the process of manufacture of the same quite soon after the tube is formed and before the glue or adhesive used in cementing the plies or layers of paper together has set.

The suspending hook designated generally by the numeral 8 is preferably formed of a piece of wire of suitable gauge folded upon itself to provide a hook portion 9, the bight of the fold constituting the bill 10 of the hook. The strands are brought together and twisted in at least a part of the shank portion 11, the lower ends of the strands of the shank being offset at 12 relative to each other. The offset portions 12 terminate in downwardly extending arms 13 curved upwardly at their lower ends 14 to form the vertical arms 15 terminating in inwardly projecting prongs 16 piercingly engaging the yoke. The arms 13 and 15 and connecting portion 14 together constitute a U-shaped clamp embracingly and supportingly engaging the central collapsed portion 3 of the yoke, to support the yoke and retain the central portion in collapsed condition. In assembling the suspending hook to the yoke the arms 15 are slightly bent outwardly from the arms 13, the collapsed central portion 3 of the yoke inserted therebetween into engagement with the connecting portion 14 after which the arms 15 are readily clamped upon the arms 13 in simple manner by the use of any suitable tool. During this operation the prongs 16 piercingly engage the yoke and securely connect the same to the suspending hook.

For suspending a garment from below the

yoke arms 2 of the hanger, each of the arms may be provided with a garment supporting member 161 provided with a loop portion 17 at its lower end for receiving a safety pin or the like and with a hook portion 18 at its upper end inserted through a hole in the side wall of the arm.

The foregoing structures are characterized by inexpensiveness of production thereof, by their rigidity, resistance to displacement and effectiveness in smoothly supporting garments notwithstanding their simplicity and inexpensiveness thereof. The operation of assembling the parts may be readily performed and once assembled the hanger is capable of repeated use without likelihood of coming apart or becoming unstable.

I have illustrated and described my invention in an embodiment thereof which I have found very satisfactory. I have not attempted to illustrate or describe certain other modifications or adaptations as it is believed that this disclosure will enable those skilled in the art to embody or adapt the invention as may be desired.

Having thus described my invention, what I claim as new and desire to secure by Letters Patent, is:

1. In a garment hanger, the combination of a supporting yoke and a suspending hook, said yoke being of tubular cross section and of fibrous material and having downwardly diverging garment supporting arms, the central portion of the yoke at the apex thereof having its side walls collapsed horizontally into vertically parallel abutting relation, said suspending hook being formed of wire folded upon itself with the bight of the fold constituting the bill of the hook, the strands of the folded wire being twisted together at the shank and laterally offset below the twist and terminating in downwardly extending arms folded upwardly at their lower ends to form upwardly opening clamp members terminating in inwardly projecting prongs, said clamp members embracingly engaging the exterior of the horizontally collapsed central portion of the yoke and clampingly retaining the side walls of the collapsed portion in vertically parallel abutting relation at the bottom edge of the collapsed central portion and upwardly therefrom, and said inwardly projecting prongs being disposed transversely of and piercingly engaging said collapsed central portion to retain the same in said clamp members.

2. In a garment hanger, the combination of a supporting yoke, and a suspending hook, said yoke being of tubular cross section and of fibrous material and having downwardly diverging garment supporting arms, the central portion of the yoke at the apex thereof having its side walls collapsed horizontally into abutting relation, said suspending hook having a hook portion and a shank portion provided with downwardly projecting arms folded upwardly at their lower ends to form laterally spaced upwardly opening clamp members terminating in inwardly projecting prongs, said clamp members embracingly engaging the exterior of the horizontally collapsed central portion of the yoke and clampingly retaining the side

walls of the collapsed portion in vertically parallel abutting relation at the bottom edge of the collapsed central portion and upwardly therefrom, and said inwardly projecting prongs being disposed transversely of and piercingly engaging said central portion to retain the same in said clamp members.

3. In a garment hanger, the combination of a supporting yoke and a suspending hook, said yoke being of tubular cross section and of fibrous material and having downwardly diverging garment supporting arms, the central portion of the yoke at the apex thereof having its side walls horizontally collapsed into vertically parallel abutting relation, said suspending hook having a hook portion and a depending shank portion provided with downwardly projecting arms folded upwardly at their lower ends to form laterally spaced upwardly opening clamp members terminating in inwardly projecting prongs, said laterally spaced clamping members embracingly engaging the exterior of the horizontally collapsed central portion of the yoke and clampingly retaining the side walls of the collapsed portion in vertically parallel abutting relation at the bottom edge of the collapsed central portion and upwardly therefrom.

4. In a garment hanger, the combination of a supporting yoke and a suspending hook, said yoke being of fibrous material and of tubular cross section and having downwardly diverging arms, said suspending hook being connected to the yoke at the apex thereof, said yoke in spaced relation from but closely adjacent to and on opposite sides of the apex having downwardly bent portions, said yoke having its side walls at the apex thereof and intermediate said downwardly bent portions collapsed into substantially vertically parallel relation and supportingly engaged by said suspending hook, the under wall of said downwardly bent portions being centrally collapsed longitudinally of the yoke into substantially abutting relation with the upper wall to provide longitudinal groove-like recesses in the under wall in said downwardly bent portions, said yoke at the outer ends of the arms thereof having downwardly bent portions, the under wall of said last named downwardly bent portions being centrally collapsed longitudinally of the yoke into substantially abutting relation with the upper wall to provide longitudinal groove-like recesses in the under wall in said last named downwardly bent portions.

WALTER LUDWIG.
